RADIO RECEIVER

Christopher M. Daly, Bridgeport, Conn.

Application October 2, 1929. Serial No. 396,673

7 Claims. (Cl. 250—20)

This invention relates to radio devices, and more particularly, to improved means for tuning and controlling the volume of broadcast receivers.

5 An object of this invention is to provide a single control for both tuning-in a station and varying the volume of the output of a radio-receiving set, thereby producing a single control and making it possible to reduce the manufacturing cost of the set. Further, the single control may be very conveniently operated from a remote point and without any complicated wiring system of remote control. Accordingly, in 10 some aspects of the invention, the one single control device may be either at the set or at a remote point, and yet any station within the range of the receiving set may be tuned-in and at any desired volume.

This object of the invention is accomplished 20 by interconnecting the means for varying the inductance in the set to tune-in a station with the means for varying the volume of the output of the set, so that for each predetermined increment of movement of the tuning means, 25 the volume-varying means moves through a complete cycle from maximum to minimum volume output. Preferably, these two interconnected devices are provided with a shaft carrying a 30 knob or finger-piece which is mounted on the set in accessible position for manual operation and/or which is driven by a motor, the operation of which is controlled by a switch located at a remote point.

The switch for connecting the set to the 35 source or sources of current supply is not ordinarily termed a control device, and may be provided along with the single control device above referred to within the scope of this invention. However, the present invention in some of its 40 forms obviates the need for this separate main switch and places it also under the control of the single control device. This is accomplished by interconnecting the means for controlling the main switch with the means for tuning-in 45 and the means for varying the volume, so that at one or both ends of the range of movement of the tuning means the main switch is opened to shut-off or render the set inoperative.

This feature is particularly advantageous in 50 the forms of the present invention employing remote control, for, while the main switch shuts off the set, it does not open the remote control circuit, leaving the latter to be controlled solely by the remote control button or buttons. Thus, 55 assuming that the main switch is open, to oper-

ate the set from a remote point the remote control button is closed to cause the motor to operate, and this in turn moves the tuning device to first cause the main switch to be closed and then to adjust the tuning condensers to 60 tune-in the desired station.

Other features and advantages will herein-after appear.

In the accompanying drawings which show a preferred form of this invention— 65

Fig. 1 is a diagrammatic view of a radio-receiving set with parts of the present invention applied thereto.

Fig. 2 is a plan view of parts of the present invention, showing them in relation to a gang 70 of condensers.

Fig. 3 is a front view of the volume-regulating potentiometer, showing the means for operating it.

Fig. 4 is a detailed view, showing the means 75 for mounting the potentiometer and the manner in which the parts are insulated from each other.

Fig. 5 is a detail diagrammatic view of the 80 potentiometer.

The radio-receiving set, diagrammatically indicated in Fig. 1, is of the tuned radio-frequency type which was selected merely for illustrative purposes. Any other type of tuned set, the volume of which may be regulated, might 85 have been used instead.

Briefly described, the set comprises five thermionic devices or valves 10, the filaments 11 of which have their respective ends connected 90 to wires 12 and 13 leading to a battery or other source of E. M. F. 14 by means of which the thermionic devices may be heated. The device also comprises an antenna coupling coil or inductance 15, in advance of the first valve 10, and transformers or coupling coils 16 and 17 between the valves, the transformers 16 being for radio-frequency while the transformers 17 are placed after the detector valve and are for audio-frequency. The plates 18 of the valves are connected through the primaries of the 100 transformers or otherwise by wires 19 leading to the positive side of a B battery or source of plate E. M. F. 20, the negative side of which is connected by a wire 21 to the wire 13 leading to the positive side of the filament current supply 14. The wire 19 for the last valve 10 has inserted in it in series with the plate and source of E. M. F. 20 a loud-speaker or other sound-producing device 22.

The set is tuned to respond to the desired 110

5 frequencies of radio transmission or broadcasting by condensers 23 placed across the secondaries 24 of the coupling devices 15 and 16, being connected to the latter by wires 26 at one side and at the other side, as diagrammatically indicated in Fig. 1, by wires 26 connected to the common wire 12, the latter being connected by wires 27 to the secondaries 24.

10 In the type of radio-receiving set illustrated, the set may be rendered inoperative by interrupting the supply of current 14 which heats the filaments 11 of the valves 10. This is done by placing a switch 28 in series with the battery or other source 14 and the feed wire 13 leading 15 to the filaments, so that by closing the switch, current causes the filaments 11 to be heated, and likewise when the switch is opened the filaments cool off. This switch, as heretofore provided, was manually operative by a finger-piece 20 or lever provided on the control panel of the set.

19 This type of set is so well known that it requires no further illustration or description. It suffices to say that the output volume of the set 25 represented by the volume of sound emitted from the loud-speaker 22 is controlled by a potentiometer P inserted between the grid 29 of the first valve 10 and the negative filament wire 12 being connected to the grid by a wire 30 and to the negative filament 12 by a wire 31. The form of potentiometer herein illustrated 30 constitutes a part of the present invention and will be described below.

35 It is also noted that for convenience in operation and to reduce the cost of making the set, the three or more condensers 23 are balanced relatively and ganged so as to be operable by a single operating device. This arrangement is illustrated in Fig. 2, in which stator plates 32 of the condensers 23 are placed one behind the other and are supported by a common supporting frame 33, while the rotor plates 34 are mounted on a common shaft 35 having 40 bearings 36 in the end plates 37 of the frame 33. The plates 34, being all connected together in electrical contact with the shaft 35, require only one wire 26 to connect them to the wire 12 to which the secondaries 24 are connected by the wire 27, and this wire 26 has a pig-tail or other flexible connection 38 with the shaft 35.

45 The forward end of the shaft is provided with an operating knob 39 by means of which the shaft may be turned to vary the setting of the condensers, and this setting may be indicated by a dial 40 secured to the operating shaft 35.

50 It should be understood that the specific type of condenser arrangement shown and above described is merely for illustrative purposes and that any other suitable type may be employed. Moreover, the handle or knob 39 may be mounted independently of the shaft 35 and any motion transmitting train desired may be provided between the handle and shaft without departing from the spirit of the present invention.

55 As stated above, one of the many objects of the present invention is to provide a single control device for tuning-in and for controlling the output volume of the set. To carry out this object, the present invention couples the potentiometer P and tuning condensers 23 in such a way that, for each predetermined increment of movement of the condensers, the potentiometer moves through its complete cycle from maximum to minimum.

60 Accordingly, as shown herein, the condenser

65 shaft 35 is provided with a gear 41 meshing with a gear 42 secured to a disk 43 carrying the resistor of the potentiometer and rotating with a shaft 44 having a bearing 45 which is secured to the end-piece 37 of the condenser frame, so that the movements of the disk 43 of the potentiometer and the rotor plates 34 of the condenser will be in coordination.

70 The specific type of potentiometer P illustrated herein comprises, as stated, the disk 43. This is made of insulating material and carries on its face resistance material 46. This may be in the form of a high resistance wire, or of carbon in block or deposited form, electrically connected by a member 47 to the shaft 44 on which the disk is mounted. Spaced from the disk 43 and member 47 by an insulating washer 48 is a flexible metal disk 49 which overlies the resistance element 46 and which is held in position to rotate with the disk 43 and shaft 44 by a washer 50 interposed between the metal disk 49 and a head 51 on the shaft 44.

75 Only one point of the metal disk 49 is at any time held in contact with the resistor 46, and this is done by means of a roller 52 mounted on a shaft 53 rotatably mounted in a bearing 54. The roller 52 is located in such position with relation to the disks 43 and 49 that it causes the flexible disk 49 to be bowed inwardly at its point of contact so that the disk engages the resistor. When the shaft 44 is rotated, the successive portions of the disk 49 are pressed against the resistor 46, and thus the disk 49 is connected with the resistor at a point closer to or farther from the point at which the member 47 is connected and this takes place without any rubbing or frictional contact between the plate 49 and the resistor 46. The shaft 44 and member 47 are connected to the wire 31 which, by reference to Fig. 1, will be seen to lead to the common wire 13, while the roller 52 is connected by the wire 30 to the grid 29 of the first valve 10.

80 The ratio of the gearing 41-42 between the operating shaft 35 and the potentiometer shaft 44 may be such that for one or two degrees of movement of the shaft 35, the disks 43-49 of the potentiometer will make one complete revolution. However, in order that an excessively high gear ratio will not be needed, the potentiometer is so arranged that a fraction of a 85 complete revolution of the disks 43-49 is all that is needed to shift the potentiometer from maximum to minimum positions. For this purpose, the electrical resistance of the resistor 46 is made of high value and the member 47 is provided with a plurality of arms 55, there being eight in the specific embodiment of the invention shown herein, for connection to the resistor at eight equally spaced places in its length and requiring 60° movements for the plate 49 90 to contact with the sections 56 of the resistor between the arms 55.

95 Of course, the resistance in the circuit including the wires 36 and 31 depends upon the shortest electrical path between the point of contact of the disk 49 with the resistor section 56 and the arms 55 of the member 47. Consequently, when the potentiometer is in the position indicated diagrammatically in Fig. 1, (the brush 57 substituting for the point of contact of the plate 49 with the resistor) no resistance is added to the circuit by the resistor 46. When, however, the disk 43 is moved in either direction from that shown in Fig. 1, resistance is added to the circuit in proportion to the amount of movement 100 105 110 115 120 125 130 135 140 145 150

and gradually as the movement progresses until maximum resistance is obtained when the contact point (brush 57) is mid-way between the points of connection or the arms 55 with the resistor 46, as shown in Fig. 5. The continued movement of the disks 43 and 49 in either direction from this point causes the amount of resistance placed in the circuit by the resistor 46 to decrease. It will thus be seen that for every 10 $22\frac{1}{2}^{\circ}$ of movement of the disk 43, the effective resistance of the resistor 46 is changed from maximum to minimum and gradually so as the movement takes place.

With this provision, it will be seen that it is only necessary to have a gear ratio of 10:1 between the potentiometer shaft 44 and the condenser shaft 35, and that for every three degrees of movement of the condenser shaft, the potentiometer is adjusted through its complete range.

20 The number of arms 55 or common connecting points of the resistor 46, and the ratio of the gearing above referred to, has been selected arbitrarily to exemplify the invention, and it should be understood that a greater or lesser 25 number of connected points and a vastly different ratio of gearing may be used if desired. The specific arrangement employed would depend largely upon the sensitivity of the set and the proximity of one station to another in the band 30 of frequencies within which the set is designed to operate.

As above described, it will be seen that since 35 complete volume control may be obtained with three degrees of movement of the operating shaft 35, with certain types of sets it is possible to remain fairly well tuned on a station while adjusting within these three degrees of movement to vary the volume.

As stated above, another object of the present 40 invention is to provide a single means for tuning and/or controlling the volume of the set, and for rendering the set operative and inoperative so that but solely one operating member need be provided on the control panel of the set.

45 To accomplish this, the present invention provides a disk 58 on the operating shaft 35 having one or more cams 59 located in position to engage a movable arm 60 of the switch 28 which, as stated above, is interposed in the current 50 supply circuit of the set.

In the form shown, where the operating shaft 35 moves between fixed limits of movement of approximately 180° , there are two of these cams 59 located substantially diametrically opposite 55 each other. These cams are so placed on the shaft 35 that when the shaft has been turned to the position where the rotor plates 34 are completely removed from between the stator plates 32, a slight further movement of the shaft 60 will cause one of the cams 59 to raise the arm 60 of the switch from the stationary arm 61 thereof and open the current supply circuit. The other cam 59 is so placed that when the 65 rotor plates are completely located between the stator plates, slight farther movement will cause that cam to raise the movable arm 60 of the switch. With this arrangement, when it is desired to shut off the set, the knob 39 on the shaft 35 is rotated in either direction to the 70 limit of its movement, whereupon the set is rendered inoperative by the opening of the current supply circuit, and when it is desired to again use the set, the set is automatically made operative by the supply circuit when the knob 39 is 75 rotated to tune in the desired station. Of

course, it should be understood that where a set is operated from house current, in which case rectifiers and transformers are used instead of batteries, the switch 28 opens and closes the current supply circuit to the rectifiers and 80 transformers.

The present invention also embraces the operation of the single control from a remote point so that the set may be tuned-in and have its volume controlled from one or more points in 85 the house.

To accomplish this in a simple expeditious manner, the present invention provides a motor 62 which drives the operating shaft 35. For this purpose, the motor may be provided with a worm 63 meshing with a worm-wheel 64 carried by a shaft 65 mounted in bearings 66 and having a spring actuated clutch disk 67 engaging a driving disk 68 on the operating shaft 35, the clutch 67-68 being provided so that the operating shaft 90 may be adjusted in spite of the fact that the motor is connected thereto by the worm and worm-wheel.

The motor 62 is of the reversible type and may be connected to a source of current supply by 95 wires 69-70. For controlling the motor from a remote point, so that it may be reversible from that point, three wires 71, 72 and 73 are led from the motor to a station S where a switch 74 is provided. This switch has an actuating member 100 or button 75 connected to the common return wire 73 and movable so as to either engage a contact 76 on the wire 71 or a contact 77 on the wire 73 to cause the motor to operate in either one direction or the other. Thus, by moving the 105 switch handle 75 in one direction, the operating shaft 35 will be caused to move say in clockwise direction. This will cause the rotor plates 34 to move from between the stator plates 32 and tune-in a station. When the station has been 110 tuned-in, the shaft 35 may be operated by the motor either forwardly or backwardly to control the volume by manipulating the handle 75. Should the handle be pressed in the direction which would not permit the shaft 35 to operate 115 because it was at one limit of its movement, the clutch 67-68 would slip and, not hearing the set operate, the user would know that the handle 75 must be operated in the other direction.

As soon as the shaft 35 begins to move from one of its extreme positions, the switch 28 will be closed by the movement of the cam 59 away from the operating arm 60 of the switch. When it is desired to turn the set off, the handle 75 is held depressed sufficiently long to cause the shaft 35 to reach the limit of its movement in the direction operated, at which time the switch 28 is opened automatically by the engagement of the cams 59 on the motor and drive shaft 35.

Variations and modifications may be made 135 within the scope of this invention and portions of the improvements may be used without others.

Having thus described the invention, what is claimed as new and for which it is desired to obtain Letters Patent, is:—

1. In a radio-receiving set, an operating device; a plurality of condensers rotated by the rotation of said device to tune the set to the frequency of the signal desired to be received; a variable resistor having a movable member for 145 adjusting the resistance in a portion of the circuit of the set to optionally increase or decrease the volume of the signal received; and means connecting the movable member of the resistor to said operating device whereby movement of 150

the latter adjusts the condensers and operates the movable member of the resistor through a complete cycle of volume control from maximum to minimum for each one of a large number of small adjustments of the condensers.

2. In a radio-receiving set, an operating device; a plurality of condensers rotated by the rotation of said device to tune the set to the frequency of the signal desired to be received; a variable resistor having a movable member for adjusting the resistance in a portion of the circuit of the set to optionally increase or decrease the volume of the signal received; means connecting the movable member to said operating device whereby movement of the latter adjusts the condensers and operates the movable member of the resistor through a complete cycle of volume control from maximum to minimum for each one of a large number of small adjustments of the condensers; a motor for operating said device; and a remote control circuit including a switch member for operating the motor.

3. In a radio-receiving set, an operating device; a plurality of condensers rotated by the rotation of said device to tune the set to the frequency of the signal desired to be received; a variable resistor having a movable member for adjusting the resistance in a portion of the circuit of the set to optionally increase or decrease the volume of the signal received; means connecting the movable member to said operating device whereby movement of the latter adjusts the condensers and operates the movable member of the resistor through a complete cycle of volume control from maximum to minimum for each one of a large number of small adjustments of the condensers; a motor for operating said device; a remote control circuit including a switch member for controlling the motor; a main switch for connecting the set to sources of electromotive force; and means controlled by said operating device for operating said main switch.

4. In a radio-receiving set, tuning means for adjusting the set to the frequency of the signal desired to be received; volume control means other than the tuning means for optionally increasing or decreasing the volume of the signal received; and a single operating device for adjusting the tuning means and for adjusting the volume control means through a complete cycle of volume control from maximum to minimum for each one of a large number of small adjustments of the condensers.

55

60

65

70

75

5. In a radio-receiving set, tuning means for adjusting the set to receive signals of any frequency over a given range of frequencies to tune in a station; volume control means other than the tuning means for varying the output of the set between maximum and minimum volumes; and means interconnecting the tuning means and volume control means for simultaneous movement and in such relative amounts that the volume control means moves through its complete range between maximum and minimum volume positions for each of a plurality of relatively small predetermined increments of movement of the tuning means, within which increment of movement of the tuning means the latter maintains the set in tune with the particular frequency of a station being received.

6. In a radio-receiving set, an operating device; a plurality of condensers rotated by the rotation of said operating device to tune the set to the frequency of the signal desired to be received; a variable resistor having a movable member for adjusting the resistance in a portion of the circuit of the set to optionally increase or decrease the volume of the signal received; and gearing connecting the movable member of the resistor to said operating device whereby movement of the latter adjusts the condensers and operates the movable member of the resistor through a complete cycle of volume control from maximum to minimum for each one of a large number of small adjustments of the condensers.

7. In a radio-receiving set, tuning means for adjusting the set to receive signals of any frequency from a given range of frequencies to tune in a station, volume control means for varying the output of the set between maximum and minimum volumes; a main control switch for connecting the set to sources of electromotive force; means interconnecting the tuning means, the volume control means, and the main switch for coordinate movement so that the volume control means moves through its complete range between maximum and minimum volume positions for each of a plurality of relatively small predetermined increments of movement of the tuning means; a reversible motor for driving the tuning means; and remote control means for the motor including motor reversing means for causing the tuning means to be operated at will in either direction.
